(57) **CLAIM**

We claim the ornamental design for peg, as shown.

DESCRIPTION

FIG. 1 is an isometric view of a closed embodiment peg in accordance with our new design;

FIG. 2 is a side elevation view thereof;

FIG. 3 is a side elevation view thereof, for the side opposite that of FIG. 2;

FIG. 4 is a top elevation view thereof;

FIG. 5 is a bottom elevation view thereof;

FIG. 6 is a front view thereof;

FIG. 7 is a rear view thereof;

FIG. 8 is an isometric view of an open embodiment peg in accordance with our new design;

FIG. 9 is a side elevation view thereof;

FIG. 10 is a side elevation view thereof, for the side opposite that of FIG. 2;

FIG. 11 is a top elevation view thereof;

FIG. 12 is a bottom elevation view thereof;

FIG. 13 is a front view thereof; and,

FIG. 14 is a rear view thereof;

The broken lines shown in the drawings are only provided to illustrate the environment of the design, and form no part of the claimed design.
